DESIGN FOR A ROOF FOR A VEHICLE BODY

Paul E. Hawkins, Lakewood, Ohio, assignor to
The Baker-Raulang Company, Cleveland,
Ohio, a corporation of Ohio

Application August 13, 1937, Serial No. 71,060

Term of patent 3½ years

To all whom it may concern:

Be it known that I, Paul E. Hawkins, a citizen of the United States, residing at Lakewood, in the county of Cuyahoga and State of Ohio, have invented a new, original, and ornamental Design for a Roof for a Vehicle Body, of which the following is a specification, reference being had to the accompanying drawings, forming part thereof.

Fig. 1 is a top perspective view of a roof for a vehicle body showing my new design;

Fig. 2 is a top plan view thereof;

Fig. 3 is a side elevational view;
Fig. 4 is a rear elevational view; and
Fig. 5 is a front elevational view.

The dominant feature of the design consists of providing the front wall of the roof with an upper vertically disposed portion and a lower rounded or convex portion in connected relation to the upper portion.

I claim:

The ornamental design for a roof for a vehicle body, as shown.

PAUL E. HAWKINS.
